UNITED STATES PATENT OFFICE.

RICHARD H. RICE, OF LYNN, MASSACHUSETTS, ASSIGNEE TO GENERAL ELECTRIC COMPANY, A CORPORATION OF NEW YORK.

HYDRAULIC VALVE-GEAR.

1,143,437.

Specification of Letters Patent. Patented June 15, 1915.

Application filed December 29, 1914. Serial No. 879,573.

To all whom it may concern:

Be it known that I, RICHARD H. RICE, a citizen of the United States, residing at Lynn, county of Essex, State of Massachusetts, have invented certain new and useful Improvements in Hydraulic Valve-Gears, of which the following is a specification.

The present invention relates to hydraulic valve gear of the type having a piston and cylinder, one of which is connected to the valve and moves relative to the other, the admission of fluid to the cylinder on opposite sides of the piston being controlled by a pilot valve which in turn is moved by a governor other controlling means.

The primary object of the invention is to provide an improved arrangement which is simple in structure, composed of few parts and can be manufactured at a relatively low cost, and which, due to its simplicity and the few parts required, gives a more perfect control of the governor over the regulating mechanism, and a longer effective life.

For a consideration of what I believe to be novel and my invention, attention is directed to the accompanying specification and the claims appended thereto.

The accompanying drawing is a sectional view of one form which my invention may take.

In the drawing 1 indicates a valve structure for controlling a supply of fluid for any purpose. For example, it may be for controlling the admission of steam to an elastic-fluid turbine. The arrangement shown may be taken as typical of any suitable structure and since the specific arrangement forms no part of the present invention, further description is unnecessary. Carried by the cover of the valve structure or other suitable part, and preferably formed integral therewith, is a tubular support 2, upon the upper end of which is formed or supported a cylinder 3. This cylinder has a head or cover 4 formed with a projecting guide member 5. Inside the cylinder 3 is a piston 6 having a stem 7 which projects both above and below it and has a fluid tight sliding fit with the tubular support 2 and with the guide member 5. The lower end of the stem is connected to the valve mechanism. In the present instance it is shown directly connected, the stem 7 being in alignment with the valve stem. The stem 7 is tubular for the greater portion of its length, 55 being closed only at the lower end.

8 is a valve stem carrying the spaced valve bodies 9 and 10 which slide with the tubular portion of the stem 7 and control the ports 11 and 12. These ports connect the cylinder on opposite sides of the piston 6 with the bore of stem 7. The valve stem 8 is provided with an axial bore 13 extending from its lower end to a point between the valve bodies 9 and 10, and with an opening 14 or openings 14 which connect the bore 13 with the space between said valve bodies. Just below the lower end of stem 8, the piston stem 7 is provided with an opening or openings 15 which connect the interior thereof with a chamber 16 formed in the support 2. The lower end of the stem 8 is enlarged as at 8' to make a fluid tight sliding fit with the stem 7. This forms a chamber 17 between the upper edge of the enlarged portion 16 and the valve body 10. The guide member 5 is cored out to form a chamber 18 and above this chamber the stem 8 has a fluid tight sliding fit with the bore of the guide member, as shown at 19. The chamber 18 is in communication with the annular space or chamber 20 between the stems 7 and 8 above the valve body 9, and this space or chamber 20 is connected with the chamber 17 by means of the passage 21.

22 is a pipe connected with the chamber 18 for the admission of operating fluid to the mechanism and 23 is a pipe connected with chamber 16 and through which the operating fluid is discharged. The operating fluid 90 may be discharged from pipe 23 at atmospheric pressure or other suitable pressure.

24 is a drain pipe connecting space 25 at the upper end of the guide member 5 to the discharge pipe 23.

The upper end of stem 8 is connected to a governor lever 26, which in turn is connected with a suitable governor 27. In the present instance an ordinary type of governor responsive to speed is shown, but it will be understood that a governor responsive to any other operating condition of the machine on which the valve gear is placed, as for example a governor responsive to pressure, or suction, may be used.

The operation is as follows. In the draw-

ing the valve bodies 9 and 10 are shown as covering ports 11 and 12 and the parts are at rest. The flow of operating fluid is completely cut off. If now the governor operates to raise the stem 8 so as to uncover ports 11 and 12, the space below the piston 6 will be connected with the source of fluid pressure through port 12, chamber 17, passage 21, annular space 20 and pipe 22. At the same time, the space above the piston will be connected to the discharge pipe 23 by way of port 11, the space between the valve bodies 9, 10, openings 14, bore 13, openings 15 and chamber 16. The fluid entering under the piston 6 will raise it, the fluid above the piston being forced out through pipe 23. The movement of the piston acts to operate the valve mechanism 1, opening it in the arrangement shown. As the piston moves, the ports 11 and 12 are moved with it, and after moving a predetermined amount, depending upon the amount which the governor has moved the stem 8, they will again be covered by the valve bodies 9 and 10. The parts will then come to rest. Should the governor operate in the opposite sense to lower the stem 8, the operation would be the same, except in a reverse direction, the space above the piston being connected to pipe 22, and that below the piston to pipe 23. It will be noted that while a movement of the governor is necessary to uncover the ports 10 and 11 to cause the mechanism to operate, it need not move to close them as the movement of the piston 6 which operates the valve mechanism 1 performs this function. In other words, the arrangement embodies the principle of the well known follow-up device common with regulating mechanisms of this general type, the purpose of which is to prevent over regulation or "hunting." It avoids, however, the use of the numerous lever and link connections heretofore required, accomplishing the same result in a much simpler manner.

When oil is used as the operating fluid it will also serve to lubricate the various sliding parts, which parts are provided with circumferential grooves, as shown, in order to render them more nearly fluid tight. Any fluid escaping from chamber 18 up into chamber 25 is drained off through pipe 24 to the discharge pipe 23.

Viewed in one aspect the valve bodies 9, 10 and the coöperating parts having the ports 11, 12 constitute in substance the pilot valve of the hydraulic motor. The piston carries the parts having the ports 11 and 12, which parts constitute the sleeve of the pilot valve. The piston and cylinder are preferably concentric with the pilot valve.

While in the present instance the stem of the motor is shown as being in line with the valve stem and directly connected thereto,

it will be understood that the invention is not limited to this arrangement and that the connection may be through a suitable lever-age arrangement if found desirable.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States is,

1. In a fluid motor, the combination of a cylinder, a piston, a hollow stem projecting on opposite sides of the piston and provided with openings through its wall above and below the piston, a second stem projecting into the hollow stem and having spaced valve bodies thereon which normally cover said openings, said second stem having a bore which connects with the space between said valve bodies, passages connecting the spaces on the outer sides of said valve bodies to each other, and admission and discharge pipes connected to said passages and bore.

2. In a fluid motor, the combination of a cylinder, a piston, a hollow stem projecting on opposite sides of the piston and having openings through its wall which communicate with the cylinder on opposite sides of the piston, a second stem projecting into the hollow stem and having spaced valve bodies thereon which normally cover said openings, and an axial bore connected with the space between the valve bodies, portions of said second stem above and below the valve bodies being of lesser diameter than the bore of said hollow stem so as to form annular chambers between them, means forming a passage which connects said annular chambers to each other, and fluid pressure conduits communicating with the chambers and the axial bore in the second stem.

3. In a valve gear, the combination with a valve comprising a casing and a valve body, of a fluid motor mounted directly on said casing with its stem in line with and directly connected to said valve body, said fluid motor comprising a cylinder, a piston which carries the stem, said stem projecting on opposite sides of the piston and being hollow and provided with openings through its wall on opposite sides of the piston, a pilot valve stem projecting into the hollow stem and having spaced valve bodies which normally cover said openings, said pilot valve stem being of lesser diameter than the bore of the piston stem so as to form annular chambers between the valve bodies and on opposite sides thereof, means forming a passage which connects the spaces on op-

posite sides of the valve bodies to each other, a bore in the pilot valve stem which connects with the space between the valve bodies, and fluid pressure conduits which communicate with the spaces on opposite sides of the valve bodies and with said bore.

5 In witness whereof, I have hereunto set

my hand this twenty fourth day of December, 1914.

RICHARD H. RICE.
